UNITED STATES PATENT OFFICE.

WILHELM SCHMIDT, OF WILHELMSHÖHE, NEAR CASSEL, GERMANY.

SUPERHEATER.

No. 832,627.

Specification of Letters Patent.

Patented Oct. 9, 1906.

Application filed May 8, 1905. Serial No. 259,344.

To all whom it may concern:

Be it known that I, WILHELM SCHMIDT, a subject of the King of Prussia, German Emperor, and a resident of Wilhelmshöhe, near 5 Cassel, in the Province of Hesse-Nassau, German Empire, have invented certain new and useful Improvements in Superheaters for Marine and Locomobile Boilers with Flue-Tubes, of which the following is an exact 10 specification.

My improvements consist in the arrangement and attachment of certain tube superheaters for locomotive and locomobile boilers which are provided with flue-tubes of larger 15 diameter.

As already known, steam-superheaters consisting of steam-tubes which are arranged in the interior of some widened flue-tubes of the boiler are brought in connection with two 20 steam-chambers, the latter lying in the smoke-box or in the chimney-chamber of the boiler. These steam-chambers are connected with the superheating-tubes in the widened flue-tubes, so that one end of each superheating 25 element forming a passage for the steam to be superheated is connected with one steam-chamber and the other end of the superheating-tubes is connected with the other steam-chamber. It is also known that the steam-chambers are so arranged that the widened 30 flue-tubes in which the superheaters are lying do not cover the free entrance of the widened steam-tubes, but are arranged above or on the side of the axis of these widened steam-tubes, and in order to fasten the ends of the 35 superheating-tubes the tubes are bent upward or sideward.

It was hitherto the great question in which simple manner the superheating-tubes were 40 to be fastened to the steam-chambers; and my improvements consist in such a simple means for producing a steam-tight connection between the superheating-tubes and the steam-chambers.

45 In the accompanying drawings, in Figure 1 the whole arrangement is illustrated in a vertical longitudinal section of the boiler provided with the improvements. Fig. 2 is a vertical section of the superheater in larger scale. Fig. 3 is a section on line A B of Fig. 1. Fig. 4 is a horizontal section through one widened flue-tube of the boiler with an upper view of one superheating element being not attached to the steam-chambers. Fig. 5 shows one superheating element in a side view. Fig. 6 shows in a side view a section

through the attachment device of one superheating element.

m is a boiler of the locomotive or marine type provided with flue-tubes *s*. A chamber *d* and other steam-chamber *d'* are arranged in the smoke-box *m'* of the boiler, the outflow and the inflow of the steam being at the under side of these chambers, as shown in Fig. 3. The steam coming from the boiler 65 through a passage (not shown in the drawings) enters the chamber *d* and passes through the openings *o* into the tubes *a*. These tubes *a* are bent at *a'* in a horizontal direction and in the same manner sideward, 70 whereafter they enter the widened flue-tube *s* with the part *a''*, as shown in Figs. 1, 2, and 4. At the end *k''* the passage of the steam is bent upward or downward, and the steam having passed the tube *a''* passes the tube *a''*, 75 arranged parallelly to the tube *a'*. This tube *a''* after having left the flue-tube *s* is bent sideward in the same direction at *a''* and forms the ring *l*, through which the steam passes. Then a bending of the tube at *a''* is 80 made, and the steam passes from there to the tube *a''* and then downward to the cap *k''* through the tube *a''* until the tube leaves the flue-tube *s*. At this point the tube is again 85 bent outward at *a''* and upward, and the steam enters the part *a''* of the tube and reaches the steam-chamber *d'* through the opening *o'*. This is the universal arrangement.

With regard to the attachment the following must be mentioned. In order to obtain a steam-tight attachment of the superheating element to the steam-chambers, which is most easily to be made, in order to undo the arrangement in a very short time the following device has been provided: The tube ends *a* and *a''* of each superheating element are firmly connected by a plate *p* in such a position with each other that there is space enough between them to employ a screw-bolt *k* with screw-nut *n*. Only one screw-bolt serves for the attachment of both ends *a* and *a''* of each superheating element to the steam-chambers, and the attachment is performed by the head *t* of the screw-bolt, which is arranged in a guide *t* of the steam-chests *d* *d'*. Between the nut *n* and the plate *p* a washer *p'* is arranged.

It is easily to be seen that the superheater element is connected with the attachment 110 and that no part of the attachment mechanism is fastened to the steam-chest. There-

fore I can draw away the whole superheating element with the attachment mechanisms out of the guides *t* after having loosened the nut *n*, and in the same manner I can bring in 5 the superheating element into the guide *t* with the whole attachment mechanisms, and after having brought them in the correct position I only need to fasten the ends *a'* of the superheating elements, with their plate *p*, by 10 turning the nut *n*. This is the most important part of my invention, that I can bring in the whole element with the attachment mechanism without any loose part into the widened flue-tube *s* and to the bottom of the 15 steam-chests *d d'* by a sliding motion of the heads of the screw-bolts *k k'* in the guides *t* of the steam-chests *d d'*.

It is clear that I can use one screw-bolt or 20 any other attachment device arranged in the middle of the two ends of the steam-tubes *a* and *a'*. Whether I use one screw-bolt or different is of no influence to my invention. However, these screw-bolts must be arranged 25 between the ends of the superheater-tubes. Therefore this bolt or these bolts are considered and called by me "attachment device."

Having thus fully described the nature of my invention, what I desire to secure by Letters Patent of the United States is— 30 1. In a steam-boiler, the combination of flue-tubes, superheating-tubes therein, a steam-chest communicating with the ends of the superheating-tubes by inlet and outlet

openings, and an attachment device for securing the superheating-tubes to the steam-chest, said device being placed between the inlet and outlet ends of said tubes. 35

2. In a steam-boiler, the combination of flue-tubes, superheating-tubes therein, a steam-chest communicating with the ends of the superheating-tubes by inlet and outlet 40 openings, and an attachment device for securing the superheating-tubes to the steam-chest, said device being placed between the inlet and outlet ends of said tubes, and consisting of a screw-bolt the head of which is slid into a slot at the under side of the steam-chest. 45

3. In a steam-boiler, the combination of flue-tubes, superheating-tubes therein, a steam-chest communicating with the ends of the superheating-tubes by inlet and outlet 50 openings, and an attachment device for securing the superheating-tubes to the steam-chest, said device being placed between the inlet and outlet ends of said tubes, consisting of the screw-bolts, the heads of which are slid into a slot at the under side of the steam-chest. 55

In witness whereof I have hereunto set my hand in the presence of two witnesses.

WILHELM SCHMIDT.
